FRANCIS C. SCHWAB, OF MOUNT VERNON, NEW YORK

GAS GENERATING AND BURNING APPARATUS

Application filed December 10, 1924. Serial No. 754,911.

This invention is an improvement in apparatus for generating and burning combustible gases, and relates more particularly to the type in which the gas is generated from a liquid fuel by the action of heat. All of the gas generated may be burned adjacent to the gas generating parts and the heat there utilized for suitable purposes, or all or a major portion of the gas may be conducted away to be burned elsewhere, the heat for generating the gas being obtained from an independent source.

The main objects of my invention are to secure noiseless operation, an intensely brilliant flame without the need for refractory material, and substantially complete combustion with the maximum percentage of carbon dioxide.

The apparatus embodying my invention may be employed for a wide variety of furnaces or heaters for house heating, soft metal melting, etc., or the gas may be used for general heating or for power purposes in an internal combustion engine.

As an important feature of my invention means are provided for the delivery of liquid fuel, such for instance as fuel oil, to a passage heated to incandescence, and through which a limited amount of air flows, whereby the air is preheated and the oil is vaporized or cracked and carried along by, or partially combined with, the air before being delivered to the burners or other combustion apparatus.

Any carbon deposited in the passages from the vaporized oil will be heated to incandescence by the wall of the passage and burned to carbon monoxide, a combustible gas, or possibly to carbon dioxide, by the air passing thereover.

With some liquid fuels or in some constructions it may not be desirable to deliver enough air through the passage to consume all of the deposited carbon, or it may be desirable to add air to the generated gas beyond

the point of generation. To permit this operation I provide as a further feature of my invention a series of passages arranged in parallel, and to only one or certain of which is the oil delivered at any one time. Air may pass through all the tubes, and by delivering the oil to different passages alternately, the air flowing through the passages to which no oil is being delivered, will consume any carbonaceous deposit collected therein, and then unite with the gas produced in the passage or passages to which oil is delivered. The delivery of oil and the delivery of air to the several passages may be independently regulated as occasion may require, and continuous operation maintained.

As another feature I provide means for inducing the proper flow of air through the passages. This means may be such as permits of a wide variation in the character of the gas produced. Preferably the flow inducing means is of the injector type and is supplied with an aeroform or expansible fluid such as steam, compressed air, or illuminating gas. By using steam a type of gas analogous to water gas is produced, in which the hydrogen of the steam forms one of the combustible constituents of the resulting gas. The steam may be generated by the same source of heat that raises the gas generating passage or passages to incandescence. If illuminating or other combustible gas be employed at the injector, the burning of this gas may be used to preheat the passage before the supply of oil is admitted, and if both oil and combustible injector gas be used, a lesser amount of oil is needed for giving a desired amount of heat. The flow inducing means, if of the injector type, may be disposed before or behind the incandescent tube or tubes so as to either force or draw the air through the tube. The flow inducing means may be a suitable fan or blower, and this may be used continuously or only in starting, and until steam can be generated to operate a steam jet for inducing the

flow. If illuminating or other combustible gas be employed for inducing the flow and for preheating, the fan may be started only when this is shut off.

5 In the accompanying drawings I have illustrated rather diagrammatically a construction embodying my invention. This form is to be considered in an illustrative rather than a limiting sense, as various changes may be 10 made in the construction and arrangement of parts, and various parts together with their function, may be omitted or altered within the scope of my invention as defined in the appended claims.

15 In these drawings:

Fig. 1 is a central vertical section through one form of apparatus embodying my invention, said section being taken on the line 1—1 of Fig. 3.

20 Fig. 2 is a vertical section on the line 2—2 of Fig. 3, and

Fig. 3 is a transverse section on the line 3—3 of Fig. 1.

In the construction illustrated there is employed a retort or gas generator in the form 25 of a tube 10. This tube is shown as extending in a horizontal direction, although it is evident that it might be inclined or vertical, or in the form of a coil. Means are provided as hereinafter described, for heating at least 30 a portion of this tube or retort to incandescence, whereby oil or other liquid fuel delivered to the incandescent zone is vaporized and cracked or partly burned. The means illustrated for delivering the liquid fuel to 35 the incandescent zone is a tube 11 extending longitudinally through the outer tube 10 and terminating within the incandescent zone portion of the retort. Means are provided 40 for inducing a current of air through the tube 10 to unite with or carry along the vaporized oil.

In practice I preferably employ a plurality 45 of these generator or retort tubes 10 which are connected in parallel in the system. As shown in Fig. 3 there are five of these tubes which are connected together at the inlet end by a manifold 12 and at the outlet end by a manifold 13. Oil is delivered from a suitable 50 manifold to the plurality of oil delivering tubes 11. It is not essential that there be oil delivery for each of the tubes 10, as certain of the tubes may be employed solely for the preheating of air, while others are used 55 as generating tubes. Any suitable means may be employed for controlling the delivery of air through the several tubes 10, as for instance separate dampers 14 in the branches leading to said tubes from one of the manifolds. The delivery of oil through the several tubes 11 is controlled by suitable 60 valves 15.

In the operation of the retorts the tubes 10 are first heated to incandescence and then oil 65 is delivered to certain of them. This oil is

vaporized or cracked and is carried along by the flow of air and at the same time there may be a deposit of coke or other carbonaceous matter on the wall of the tubes receiving oil, due to the insufficient supply of air to burn 70 such carbonaceous matter. In practice the oil may be delivered through two of the three pipes 11 and the valves 15 intermittently operated so that when an objectionable amount of solid carbonaceous matter has deposited, 75 the oil in one tube may be shut off and the oil turned on in the other, whereby the flow of air in the incandescent tube having the carbonaceous deposit, will act to burn off such deposit and produce carbonic oxide gas which unites 80 with the gas produced in the other tubes at the outlet manifold 13. Preferably means are employed whereby the operator may inspect the interior of the retort tubes during operation. As shown, each tube has an extension 85 piece 16 in alignment therewith, and projecting to the exterior of the casing, and within this extension is a quartz glass window 17. The operator may look through this window 90 to watch the character of the reaction taking place in the retort, and determine the necessity for shifting the valves or dampers to burn off deposit. The portion of the extension 16 beyond the quartz window may have ports 18 through the wall thereof, whereby a small 95 amount of air may enter the casing through this outer extension and maintain the temperature of the latter comparatively low, as well as convey to the retort chamber any gas that may escape past the window.

Beyond the collecting or outlet manifold 13 a conduit 19 extends to the point where the gas is to be burned. In the specific construction illustrated the retorts are mounted within a main casing 20 which may serve as the base 105 for a household heating furnace, or for any other desired heating purposes, and the gas conduit 19 extends to burners within this casing, and so positioned as to maintain the retort tubes 10 at the proper incandescence. As 110 shown, there are a plurality of burners 21 having elongated slots or rows of apertures disposed between adjacent tubes 10, and below the same, whereby the gas from each burner passes between two adjacent tubes and then 115 upwardly to the body of the casing 20. The cross sectional area of the passages within the burners decreases from the supply end, so that there will be a substantially uniform rate of flow and a substantially uniform flame 120 throughout the length of each slot. The several burners may be connected to the gas conduit by a manifold 22. If it is desired to conduct any of the generated gas to be burned at some distant point, a conduit 23 may be employed, said conduit leading from the manifold 22 or a point adjacent thereto.

The lower portion of the casing 20 is preferably so constructed that the admission of air thereto for supporting the combustion at 125

the burner 21, may be properly regulated. As shown, the casing has an inlet 24 provided with a controlling valve 25.

The delivery manifold 12 is connected to a supply conduit 26 which may in some cases lead from the interior of the casing 20, but preferably leads from the exterior thereof. In some cases I may rely upon the chimney draft for inducing the flow of air through the supply conduit 26 and the several retorts, although it is preferable to provide means for inducing the flow at the desired rate. One means which may be employed for this purpose is an injector nozzle 27 mounted in a Venturi section 28 of the conduit 19. This nozzle is provided with means for supplying thereto an aeroform fluid which may vary according to economic conditions or the character of the apparatus in connection with which the burned gas or generated heat is to be employed. I may supply steam, compressed air, or combustible gas under pressure, to this nozzle and the character of the resultant gas will be varied accordingly. The nozzle at its outer end may have a plurality of inlets 29, 30 and 31 each having suitable controlling valves whereby steam may be delivered through the inlet 29, compressed air through the inlet 30, or illuminating or other combustible gas under pressure through the inlet 31. By using the combustible gas the latter may be used for a limited period before the oil is turned on, so that this gas will be consumed at the burners 21 and heat the tubes 10 to the vaporizing point of oil. After this preheating has taken place the oil may be turned on and the supply of gas continued or shut off and replaced by other flow inducing means.

If steam is to be employed as the flow inducing means, there is preferably provided means whereby a portion of the heat is utilized for generating the same. As shown, there is a steam generating tube 32 above the burners and having an inlet tube 33 for water under pressure. This water is admitted at the desired slow rate, so that the device operates as a flash boiler, and the steam is conducted through a pipe 34 to the steam inlet 29. There is preferably provided a safety valve 35 to prevent too high pressure in the flash boiler.

In using illuminating gas, steam, or compressed air as the injecting means, the injector may be positioned beyond the retort so as to draw air through the latter, and without having the injector fluid pass through the retort, or it may be positioned in advance of the retort so that such injector fluid does pass through the retort. For steam it is preferable that the steam jet be positioned in advance of the retort so that the steam passes through the incandescent zone.

As shown, the tube 26 has a Venturi section 36 in connection with which there is employed an injector nozzle 37 which may re-

ceive steam from the conduit 34 through a conduit 38, or may receive compressed air or compressed combustible gas such as illuminating gas through an inlet pipe 39. Beyond the injector nozzle 37 there is shown a blower 40 of the centrifugal or fan type, whereby the fan may be used alone or in conjunction with the other flow inducing means. The conduit 26 has a damper 41 whereby the amount of air admitted may be controlled, and the inlet to the blower is also preferably provided with a damper 42 for controlling the flow at this point. The blower should be of the constant speed type, whereby when the proper conditions have been established they will remain constant and not require frequent readjustment to maintain operative conditions.

With my improved apparatus very low grades of fuel oil containing asphaltum or other heavy fractions may be employed, as it will be obvious that larger or more rapid deposits of coke or other carbonaceous matter in the retort tubes will merely require a more frequent change in the cycle. During the first cycle in each retort coke is formed, while in the next succeeding cycle the oil is shut off and the coke is transformed into carbon monoxide or carbon dioxide.

Although I do not wish to be limited to any particular size of any of the parts, it is evident that there is certain critical relationship of the parts necessary for securing satisfactory operation. If the generator tubes be too large, the flow of gas therethrough will have to be correspondingly slow, or there will be too large an amount of air pass through the tubes in respect to the amount of oil converted into gas. The tubes should be of such length as to satisfactorily preheat the air before it reaches the point at which the oil is delivered. Experiments indicate that the diameter should be somewhere about one inch in order that the proper rate of flow of the air may be maintained and the tube maintained at incandescence without too great cooling effect by the air. The length of the tubes may vary within wide limits, and is dependent upon the pressure and the draft or air flow and the rate of oil flow. The limited combustion of the oil with the air in the retort tubes causes the production of carbon monoxide due to the excess of fuel, and this carbon monoxide is burned with the other fuel at the burner. Where steam is employed at the injector nozzle 37 which is in advance of the retorts, this steam, as well as the air, acts upon the incandescent coke to aid in converting the latter into carbon monoxide, some of the steam being decomposed to hydrogen and oxygen, the latter being used for partially burning the coke. The number of tubes in which the oil is being delivered will vary with the rate at which the coke is de-

5 posited and burned off. For instance if a predetermined amount of coke may be burned off in one-half the time which is required for the deposit of that amount of coke, then oil may be delivered through two of the oil tubes and shut off in only one, if three are used as illustrated.

10 The apparatus is preferably so adjusted or regulated as to produce carbon monoxide in the retorts, but it will be evident that if the coke be burned directly to carbon dioxide the heat of such burning will be advantageously used in maintaining the proper temperature of the retorts.

15 In the foregoing I have referred to the retorts being heated to incandescence. This is not essential during the vaporizing stage, as it is important that the temperature be only sufficiently high to insure the substantially complete vaporization of the oil. The use of a temperature sufficiently high to give incandescence is important during the burning off of any deposits in the retorts.

20 The same generator 32 may be used solely for the delivery of steam to the injector nozzle 27 or the injector nozzle 37 or both, and in case steam is not used as the injector means the supply of water to the steam generator may be shut off. It will of course be evident 25 that the steam generator may be employed for the continuous projection of steam, even though the steam injectors are not used. The steam generated may be conducted from the apparatus through the conduits 30, 31 or 35 39, or through other suitable means. In case the apparatus is not equipped or connected for the delivery thereto of combustible gas at the injectors, and there preheated, it will be evident that other means might be employed 40 for bringing the generator tubes up to the desired temperature. Heat may be applied to the exterior thereof from any suitable source or the oil delivered may be burned so that combustion of the oil takes place directly 45 in the retort until the wall of the latter becomes heated to the desired extent. The regulation of the air and oil supplies may then be readjusted so as to stop the direct burning at these points and to secure the main combustion at the burners 21. For igniting the combustible mixture in the retorts a spark plug or other ignition means might be employed.

50 The conduit connecting the manifolds 12 and 13 is preferably inclined and has a sump 43 into which there will drain any unvaporized oil or condensate in the system. Any such liquid may be drawn off through a valve outlet 44.

55 60 My improved apparatus possesses many advantages over other apparatus heretofore employed. Many of these will be apparent from the foregoing description. It will be noted that there is no needle point orifice for the oil, and therefore there is less liability of

65 the outlets becoming clogged, and low pressure may be employed with little or no noise. By controlling the air in relation to the flow of oil a blue or a white flame can be produced as desired. There is no liability of stoppage 70 of the operation as the oil and the supply of fuel continues, as any clogging of one pipe will not interfere with the continuous delivery of oil through the other. Comparatively 75 expensive and relatively high volatile oil is not necessary. As the apparatus has very large orifices and very low gas pressure, there is a freedom from atmospheric pulsations which are so annoying in the usual burning of oil. Thus I am able to secure uniform 80 and smokeless combustion without the usual tendency to go out.

85 It is not necessary to have incandescent furnace walls as are required in many constructions, and the rate of combustion and character of flame obtained is easily controlled by varying the rate of flow of air through the generator.

Having thus described my invention, what I claim as new and desire to secure by Letters 90 Patent is:—

1. A gas generator including a plurality of passages arranged in parallel, means for heating said passages, means for delivering air through all of said passages, and means for delivering a liquid fuel to the interior of one or more of said passages.

2. An apparatus of the class described, including a plurality of passages arranged in parallel, means for heating a zone of each passage to incandescence, a manifold for supplying air to all of said passages, a gas outlet manifold connected to the opposite ends of said passages, and means for delivering liquid fuel to the interior of one or more 105 of said passages.

3. A gas generator including a plurality of passages arranged in parallel, means for controlling the flow of air through said passages, means for controlling the delivery of liquid fuel to said passages whereby the liquid fuel may be delivered to any one or more of said passages, and a manifold connected to the outlets of all of said passages.

4. A plurality of generators each having a zone adapted to be heated to incandescence and having inlets to receive air and outlets for the delivery of gas, a manifold connected to said outlets, oil pipes terminating in certain of said generators for the delivery of oil to said incandescent zones, means for controlling the flow of oil whereby air may pass through all generators but oil may be intermittently shut off from one or more while 115 flowing to another.

5. In combination a series of generator tubes one serving for preheating air and another having an oil inlet intermediate of the ends thereof and serving for heating air 120

and vaporizing oil, and a manifold connecting the outlets of said tubes.

6. In combination, a series of generator tubes one serving for preheating air and another having an oil inlet intermediate of the ends thereof and serving for heating air and vaporizing oil, a manifold connecting the outlets of said tubes, burner means for heating all of said tubes, and means for supplying gas thereto from said manifold.

7. A gas generator including a tube, means for maintaining a draft of air therethrough, means for delivering oil to a point intermediate of the ends of the tube, means for heating the oil at said point to the vaporizing temperature of the oil, and a transparent closure for one end of the tube whereby the operation within the tube may be witnessed, a supporting casing having an aperture through which said last mentioned end of the tube extends, and apertures in the wall of said tube between said closure and the casing wall.

8. In combination, a plurality of generator tubes, a manifold connected thereto, an air supply pipe, a valve for controlling said pipe, separate dampers for controlling the delivery of air from said manifold to each of said generator tubes, and a second manifold connected to the outlet ends of each of said tubes.

9. In combination a plurality of generator tubes, means for delivering oil to certain of said tubes intermediate of the ends thereof, a manifold connected to the inlet of said tubes, an air conduit leading to said manifold and having a Venturi section and an injector nozzle for maintaining the flow of air through the tubes, burner means, and connections between said burner means and the outlets of said generator tubes.

10. In combination a plurality of generator tubes, a plurality of elongated burners each of a length substantially equal to the length of said tubes and disposed therebelow and therebetween, whereby the generator tubes are heated throughout substantially their entire length, means for delivering oil to certain of said tubes intermediate of the ends thereof, and means for delivering combustible gas from said tubes to said burners.

11. A gas generator including a series of retorts arranged in parallel and maintained at an incandescent heat, a common means for maintaining a draft of air through the retorts, independent means for delivering fuel oil to each retort, the cross sectional area of the retorts, the rate of flow and quantity of air and the rate of oil delivery being such that a substantially complete cracking and vaporizing of the oil takes place in the air current.

12. A gas generator including a series of retorts arranged in parallel and maintained at an incandescent heat, a common means for maintaining a draft of air through the retorts, independent means for delivering fuel

oil to each retort, the cross-sectional area of the retorts, the rate of flow and quantity of air and the rate of oil delivery being such that a substantially complete cracking and vaporizing of the oil takes place in the air current, and means for optionally cutting off the oil supply to any retort to permit a carbon deposit to be oxidized and burned out by the air flowing therethrough.

13. A device of the class described in claim 11, wherein a portion of the gases generated in the retorts are burned to retain the retorts at an incandescent heat.

14. A device of the class described in claim 11, wherein a steam injector is used to force air through the retorts and wherein a portion of the gas generated in the retorts is burned to generate steam for the injector.

15. A heating unit including a housing having an opening therein through which air may be drawn by the flue draft, a series of burners, a common gas manifold therefor, a battery of retorts arranged above the burners and delivering gas to said manifold, independent oil delivery pipes for introducing fuel oil to the retorts, a header from which a draft of air is maintained through all of the retorts, and means for forcing the gas produced by the vaporized oil and the air to the burners.

16. A heating unit including a housing having an opening therein through which air may be drawn by the flue draft, a series of burners, a common gas manifold therefor, a battery of retorts arranged above the burners and delivering gas to said manifold, independent oil delivery pipes for introducing fuel oil to the retorts, a header from which a draft of air is maintained through all of the retorts, and means for forcing the gas produced by the vaporized oil and the air to the burners, said retorts having sight openings therein arranged in an offset portion of the housing to permit observation of the process of reaction.

17. A heating unit including a housing having an opening therein through which air may be drawn by the flue draft, a series of burners, a common gas manifold therefor, a battery of retorts arranged above the burners and delivering gas to said manifold, independent oil delivery pipes for introducing fuel oil to the retorts, a header from which a draft of air is maintained through all of the retorts, and means for forcing the gas produced by the vaporized oil and the air to the burners, said burners including elongated trough-like members having burner slots extending throughout their length and including means for deflecting and distributing gas to produce a substantially uniform flame through the length of the slots.

18. A heating unit including a housing having an opening therein through which air may be drawn by the flue draft, a series

of burners, a common gas manifold therefor, a battery of retorts arranged above the burners and delivering gas to said manifold, independent oil delivery pipes for introducing fuel oil to the retorts, a header from which a draft of air is maintained through all of the retorts, and means for forcing the gas produced by the vaporized oil and the air to the burners, said burners being arranged intermediate pairs of retorts, whereby to maintain the retorts at an incandescent heat.

19. A heating unit including a housing having an opening therein through which air may be drawn by the flue draft, a series of burners, a common gas manifold therefor, a battery of retorts arranged above the burners and delivering gas to said manifold, independent oil delivery pipes for introducing fuel oil to the retorts, a header from which a draft of air is maintained through all of the retorts, means for forcing the gas produced by the vaporized oil and the air to the burners, means for controlling the rate of air flow through the retorts, and means for controlling the rate of flow of auxiliary air introduced by the flue draft.

20. In combination an air delivery pipe, a fan for delivering air therethrough, a manifold receiving air from said pipe, a series of generator tubes connected to said manifold, means for delivering oil to the interior of certain of said tubes, a second manifold receiving air or gas from all of said tubes, a gas delivery conduit from said manifold, a second manifold receiving gas from said last mentioned conduit, a plurality of burners connected to said last mentioned manifold and disposed below and between said tubes, means for regulating the flow of air through said tubes, and means for regulating the flow of oil to said tubes, one of said conduits having a Venturi section and an injector for expansible fluid to act in conjunction with or independently of the blower to maintain the flow of air through the tubes.

21. In combination a plurality of generator tubes, a plurality of burners, a manifold at the outlet of the tubes whereby fluid passes through the tubes in parallel, a manifold at the inlet of said burners for delivering fluid to the burners in parallel, and a conduit connecting said manifolds.

22. In combination a plurality of generator tubes, a plurality of burners, a manifold at the outlet of the tubes whereby fluid passes through the tubes in parallel, a manifold at the inlet of said burners for delivering fluid to the burners in parallel, and a conduit connecting said manifolds, said conduit having a Venturi section and an injector nozzle for an expansible aeroform fluid.

23. In combination a plurality of generator tubes, a plurality of elongated burners disposed therebelow, whereby the generator tubes are heated throughout substantially

their entire length, means for delivering oil to certain of said tubes intermediate of the ends thereof, and means for delivering combustible gas from said tubes to said burners.

Signed at New York, in the county of New York and State of New York, this 4th day of December A. D. 1924.

EDMUND A. GARRETT.
